FREDERICK BRANTIGAM, OF BRIDGEPORT, CONNECTICUT.

MACHINE FOR BENDING TUBES.

1,047,612.

Specification of Letters Patent. Patented Dec. 17, 1912.

Application filed September 16, 1911. Serial No. 649,725.

To all whom it may concern:

Be it known that I, FREDERICK BRANTIGAM, a citizen of the United States, residing at Bridgeport, county of Fairfield, State of Connecticut, have invented an Improvement in Machines for Bending Tubes, of which the following is a specification.

This invention has for its object to provide a simple easily operated and easily adjusted machine for bending tubes which shall be adapted for general use in large and small plants wherever the bending of tubing is required as in the manufacture of automobile and other frames.

In the accompanying drawing forming a part of this specification, Figure 1 is a longitudinal section illustrating the construction and operation of my novel tube bending machine; a tube having been inserted, but the bending operation not having commenced; Fig. 2, a transverse section on the line 2—2 in Fig. 1 looking in the direction of the arrows, no tube being shown; Fig. 3, a sectional view corresponding with Fig. 1 showing the manner in which the bending roll is swung in an arc of a circle to produce the required bend in a tube; Fig. 4, a similar view illustrating a modification in the details of construction; Fig. 5, a transverse section on the line 5—5 in Fig. 4 looking in the direction of the arrows; and Fig. 6 is a side elevation of the framework illustrating a variant mode of adjusting the fulcrum.

The gist of the invention lies in the use in connection with guide rolls, of a swinging bending roll and means for varying the arc of movement of the bending roll to meet the varying requirements of use.

10 denotes framework which may be of any ordinary or preferred construction, 11 a lower guide roll, 12 an upper guide roll and 13 the swinging bending roll. The guide rolls are mounted to rotate on cross rods 14 fixed in the framework. The upper guide roll is placed out of vertical alinement with the lower guide roll and inward therefrom. Tubes are bent by forcing them through the guide rolls and into engagement with the bending roll which is simultaneously caused to swing in an arc of a circle, thereby bending the tube in a curve of any desired radius within the limits of the machine. The tubes are forced through the machine in any suitable manner as by a piston 15 operated by hydraulic or pneumatic power.

In the form illustrated in Figs. 1, 2 and 3

the swinging bending roll is carried by a rod 16 which is suspended within the framework from an upper cross rod 17, by means of ropes, wire cables or chains indicated by 18. 60 Rod 16 upon which the swinging bending roll is mounted is connected by means of links 19 with a cross head 20 rigidly secured to a sliding rod 21, the rear end of which is connected to a piston 22, the forward end 65 thereof extending through and being guided and supported by the framework. 23 and 24 denote cylinders in which pistons 15 and 22 respectively reciprocate. I have shown a supply pipe 25, having a controlling valve 70 26 and branch pipes 27 and 28 leading to the respective cylinders. 29 denotes an adjustable stop on rod 21 which is adapted to engage the framework and limit the forward movement of the rod and consequently the 75 oscillation of the swinging bending roll. The arc of movement of the swinging bending roll, in this form, is determined by means of an adjustable fulcrum 30 which is adapted to be moved vertically in slots 31 in 80 the side pieces of the framework and to be locked in position by nuts 32 engaging the fulcrum, in the present instance a rod, and bearing against the side pieces of the framework. I have shown fulcrum 30 as having 85 mounted thereon rollers 33, upon which the ropes, cables or chains bear.

In the form illustrated in Figs. 4 and 5 the swinging bending roll is suspended from the fulcrum 30 and the latter is suspended from the framework. In the present instance I have shown the fulcrum as provided with a central hub 34 from which a rod 35 extends upward through the top cross piece of the framework. The upper end of this rod is threaded and said rod and fulcrum are locked at any required adjustment by means of a nut 36 engaging rod 35 and bearing upon the top cross piece of the framework. Rod 16 upon which the swinging bending roll is mounted to rotate is carried by links 37, the upper ends of which pass freely through yokes 38 which oscillate on the fulcrum, the upper ends of said links being threaded and engaged by nuts 39 which bear upon the yokes and are shown as locked in place by set nuts 40. This adjustment may be used in coöperation with the adjustment of rod 35 in determining the arc of movement of the swinging bending 110 roll.

Instead of slots 31 the side pieces of the

2
framework may be provided with a plurality of holes 41, as shown in Fig. 6, and the fulcrum instead of being moved vertically in said slots may be placed in corresponding holes 41 where it will be rigidly held in place.

The operation will be obvious from the description of the machine. In either form of the invention, tubes can be bent in curves 10 of any required radius within the capacity of the machine by adjustment of the fulcrum relatively to the bending roll.

In the form illustrated in Figs. 4 and 5 in addition to providing means for adjusting the fulcrum vertically, I provide in addition means for adjusting the bending roll 15 toward and from the fulcrum rod.

It will be noted that in all of the forms 20 of my invention illustrated in the drawing, the bending is carried by a freely swinging support eccentrically mounted with relation to the guide rollers.

Having thus described my invention I claim:

25 1. A machine of the character described comprising guide rolls, a swinging bending roll, a support for said bending roll, a variable fulcrum intermediate said support and bending roll and about which said roll will 30 swing, and means for swinging said bending roll.

35 2. A machine of the character described comprising a frame, guide rolls mounted therein, a swinging bending roll, a support in said frame for said bending roll, a fulcrum adjustably mounted in said framework intermediate of said support and said bending roll and about which said bending roll will swing, and means for swinging said 40 bending roll.

45 3. A machine of the character described comprising a frame provided with slotted side pieces, guide rolls mounted in said frame, a swinging bending roll, a support in said frame for said bending roll, a fulcrum adjustably mounted in said slots intermediate of said support and said bending roll and about which said bending roll will swing, and means for swinging said bending roll.

50 4. A machine of the character described comprising guide rolls, a swinging bending roll, a support for said bending roll, a variable fulcrum intermediate said support and bending roll and about which said roll will 55 swing, a longitudinally movable rod, and connections intermediate of said rod and

said bending roll, whereby movement of said rod causes said bending roll to swing in an arc of a circle.

60 5. A machine of the character described comprising guide rolls, a bending roll, a rod on which said roll is mounted, suspending cables to which said rod is connected, an adjustable fulcrum engaged by said cables and means for swinging the rod and bending roll in an arc of a circle of which the fulcrum is the center.

65 6. A machine of the character described comprising guide rolls, a bending roll, eccentrically hung freely swinging cables for supporting said bending roll, a fulcrum arranged to engage said cables, and means for swinging the bending roll to bring the cables and fulcrum into engagement, whereby the bending roll is swung in an arc of a 70 circle with the fulcrum as the center.

75 7. A machine of the character described comprising guide rolls, a bending roll, cables by which the bending roll is suspended, a fulcrum engaged by said cables, a reciprocating rod and connections between said rod and the bending roll whereby the latter is swung in an arc of a circle.

80 8. A machine of the character described comprising guide rolls, a bending roll, cables by which the bending roll is suspended, a fulcrum engaged by said cables, a reciprocating rod, connections between said rod and the bending roll, for the purpose set forth, 90 and a stop for limiting the forward movement of the rod.

85 9. In a machine of the character described, the combination with guide rolls, a bending roll and cables by which the bending roll is suspended, of a fulcrum engaged by said cables, a reciprocating rod and connections between said rod and the bending roll.

95 10. In a machine of the character described, the combination with guide rolls, a suspended bending roll and a fulcrum from which said roll swings in an arc of a circle, of a longitudinally moving rod connections between said rod and the bending 105 roll and a stop for limiting the forward movement of said rod.

In testimony whereof I affix my signature in presence of two witnesses.

FREDERICK BRANTIGAM.

Witnesses:

JOHN F. NEWMAN,
THOMAS L. HEALY.

It is hereby certified that in Letters Patent No. 1,047,612, granted December 17, 1912, for an improvement in "Machines for Bending Tubes," the name of the patentee was erroneously written and printed as "Frederick Brantigam," whereas said name should have been written and printed *Frederick Brautigam*; and that the said Letters Patent should be read with this correction therein that the same may conform to the record of the case in the Patent Office.

Signed and sealed this 28th day of January, A. D., 1913.

[SEAL.]

C. C. BILLINGS,

Acting Commissioner of Patents.
